UNITED STATES PATENT OFFICE.

EUGENE L. PERRY, OF NEW YORK, N. Y., ASSIGNOR TO AMERICAN STOPPER COMPANY,
A CORPORATION OF NEW JERSEY.

CAN-BODY-MAKING MACHINE.

1,143,065.

Specification of Letters Patent. Patented June 15, 1915.

Application filed October 22, 1909. Serial No. 524,085.

To all whom it may concern:

Be it known that I, EUGENE L. PERRY, a citizen of the United States, and a resident of the city of New York, county of Kings, 5 State of New York, have invented certain new and useful Improvements in Can-Body-Making Machines, of which the following is a specification.

My invention relates to can body making 10 machines.

The object of my invention is to provide a machine for automatically, rapidly and cheaply making can bodies of the kind having non-collapsible lock seams or seams of 15 the kind wherein one member of the joint is furnished with a reverse fold or lock shoulder to hold the two members of the joint, stiff and rigid, and prevent collapsing under 20 external pressure although the seam is unsoldered, such can bodies being ordinarily made from decorated blanks unsuitable for soldering.

A further object of my invention is to provide a machine which will form the bodies 25 of cans from elaborately colored or decorated blanks by interlocking the ends of said blank so as to form a perfect joint and also to bend the blank into the proper shape prior to the formation of the joint, all this to be done 30 in three operations and without in any way scratching, injuring or marring the elaborate ornamentation of the blank:

These objects are accomplished by my invention one embodiment of which is herein- 35 after described.

My invention comprises in coöperative combination a double or dovetail hook former or folder for forming a double hook or one with a reverse fold, or of a general dove- 40 tail shape, upon one end of the body blank; a hook former or folder for forming a single or plain hook upon the opposite end of the body blank; clamps for the blank while being operated upon by the hook formers 45 or folders; benders or shapers for preliminarily bending the end portions of the body blank adjacent to the hooks to facilitate the proper interengagement of the hooks when the blank is subsequently bent around the 50 horn, a body former horn preferably an expansible and collapsible one or one having a movable segment to facilitate the interen-

gagement of the hooks and their snug interlocking; a movable clamp for clamping the middle portion of the body blank against the horn; formers for doubling or bending the blank about the horn, preferably rollers to prevent marring of the decorated body blank; secondary folders or formers operating successively to bend first one free end of the blank about the horn, and then the other to cause the hooks at the ends thereof to properly interengage while the horn is collapsed and then snugly engage when the segments of the horn are expanded; a plunger or bumper for compressing the seam against the horn and causing the secondary hook or reverse fold of the dovetail hook to snugly and properly abut against, lock and stiffen the other members of the seam; a body blank conveyer for feeding or moving or conveying the blank first in position to be operated upon by the hook formers, then advancing it into position to be operated upon by the preliminary body blank benders or shapers, and then further advancing it to the horn and formers or folders which bend the blank around the horn; and a can body discharger operating after the horn is again collapsed to deliver the former can from the horn of the machine. By this coöperative combination of parts a plurality of blanks, in different stages of formation into the can body, are simultaneously operated upon, thus enabling the can bodies to be rapidly 85 and cheaply manufactured with the required non-collapsible type of lock seam and without marring or injuring the decoration of the blanks from which the can bodies are formed, one blank being operated upon by the hook forming or folding devices while another is being operated upon by the bending or shaping devices and another is being operated upon by the body former horn and devices directly coöperating therewith. 95

My invention also consists in the novel construction of parts and devices and in the novel combinations of parts and devices herein shown and described and more particularly specified in the claims.

For a more particular description reference is to be had to the accompanying drawings, forming a part hereof, in which:

Figure 1 is a plan view of a machine pro-

vided with my improvement; Fig. 2 is a front elevation of the same. Fig. 3 is a rear elevation of the same. Fig. 4 is an end elevation of the same, the end shown being that 5 on the left of the operator when feeding the machine. Fig. 5 is a plan view partially in section taken on the line 5—5 of Fig. 4 looking in the direction of the arrows. Fig. 6 is a front elevation, partially in section, of a 10 part of the machine. Fig. 6^a is a detail view of a cam hereinafter to be described. Fig. 7 is a longitudinal vertical section of a portion of the machine. Fig. 8 is a central vertical longitudinal section of the machine. 15 Fig. 9 is an enlarged plan view of one of the folders and a portion of the machine adjacent thereto. Fig. 10 is a sectional view taken on the line 10—10 of Fig. 9, looking in the direction of the arrows. Fig. 11 is a 20 plan view of the folders shown in Figs. 9 and 10, but shown on a larger scale. Fig. 12 is a front elevation of the structure shown in Fig. 11. Fig. 13 is an end elevation of the structure shown in Figs. 11 and 25 12, the view being taken at the left end. Fig. 14 is a sectional view taken on the line 14—14 of Fig. 13, looking in the direction of the arrows. Fig. 15 is a section taken on the line 15—15 of Fig. 14, looking in the direction of the arrows. Fig. 16 is a sectional view taken on the line 16—16 of Fig. 14, looking in the direction of the arrows. Fig. 30 17 is an enlarged perspective view of a portion of the folder shown in Figs. 11 to 15. Fig. 19 is a perspective view of one of the stationary members of the folder. Fig. 18 is a perspective view of a slide of the folder. Fig. 20 is a perspective view of a cam which is adapted to be placed in a groove. Figs. 40 20^a and 21 are a side elevation, partially in section, and a plan view, respectively, of a double cam. Figs. 22 and 23 are a side elevation, and plan view, respectively, of another cam. Fig. 24 shows an edge of a blank 45 adapted to be acted upon by my improved machine. Fig. 25 is a view showing the same blank in the position it occupies in the folders before they act on it. Fig. 26 shows the blank at the close of the first operation. Fig. 27 shows the position of the dies when 50 producing the product shown in Fig. 26. Fig. 28 shows the condition of the blank when the folders have acted at both ends. Fig. 29 shows the folders acting at each end 55 of the blank to produce the product shown in Fig. 28. Fig. 29^a shows the blank when it emerges from the benders. Fig. 30 shows the benders producing the product as shown in Fig. 29^a. Fig. 31 shows a modified form 60 of mechanism for driving the blank shifting parts. Figs. 32 and 33 are sectional views showing the blank-moving and holding mechanism in various positions. Fig. 34 is a plan view of one of the benders the other 65 not being shown as it is identical therewith. Fig. 35 is a sectional view taken on the line 35—35 of Fig. 34, looking in the direction of the arrows. Fig. 36 is a side elevation of the horn and bending mechanism connected therewith. Fig. 37 is a sectional view taken on the line 37—37 of Fig. 36, looking in the direction of the arrows. Fig. 38 is a sectional view taken on the line 38—38 of Fig. 37, looking in the direction of the arrows. Fig. 39 shows the blank which is illustrated 70 in Fig. 29 in position to be bent around the horn, the section being taken from the front of the horn looking toward the rear. Fig. 40 shows the first operation of bending the blank about the horn. Fig. 41 shows the 75 next operation of bending the blank about the horn. Figs. 42 and 43 show the next operation, Fig. 43 showing the blank before the horn is expanded, and Fig. 42 showing the condition just after. Fig. 44 shows the 80 joint made on the horn, pressed down and nearly in its final form. Figs. 45, 46 and 47 are detail sectional views showing in two different positions a modified construction of the folders, dies or devices which form the 85 double or dovetail hook or edge fold with reverse fold or locking shouuler upon one end of the blank. 90 Throughout the various views of the drawings, similar reference characters designate similar parts. 95 The double or dovetail hook former or folding device which produces the double hook or one with a reverse fold or secondary hook may be of any suitable construction 100 adapted to perform this function. It, however, preferably has or comprises stationary dies, folders or members 52, 53, a vertically movable die or folder 72 and a horizontally movable die or folder 43, the same operating 105 to first form a groove α in one end of the blank with parallel upright walls α^1 , α^2 and with an intermediate or connecting wall α^3 , preferably curved, as shown in Figs. 26 and 27, and then by a secondary operation of 110 these dies or folders to incline or converge the parallel walls α^1 α^2 and thus form a double or dovetail hook, or one with a secondary hook or reverse fold α^4 on this end of the 115 body blank as shown in Figs. 28 and 29. 120 The hook fornier or folder which forms a plain hook α^5 upon the opposite end of the body blank may be of any suitable kind or construction adapted to perform this function. It preferably, however, has or comprises a die or folder 94, operating in conjunction with a movable die or folder 100 as shown in Fig. 29. 125 The body blank benders or shapers which operate to bend the end portions of the blank adjacent to the hooks preferably into approximately the shape shown in Fig. 29^a may be of any suitable kind or construction adapted to perform this function. The same, however, preferably have or comprise 130

a fixed die or folder 6 operating in conjunction with a movable or rocking die or folder 140, as shown in Fig. 30.

The body former horn 8 may be of any suitable kind or construction, but is preferably of an oval shape in cross section, and of an expandable and collapsible type or composed of two segments as 219 and 218 adapted to be separated by a wedge 217 as shown for example in Figs. 39 and 40.

The body formers or benders which double or bend the body blank about the horn 8 may also be of any suitable kind or construction adapted to perform this function. The same, however, preferably consist of rotatable rollers 10, 10, mounted on the forks or arms of a reciprocating slide and adapted to be moved astride the body former horn as will be readily understood from Fig. 40 of the drawing, the rollers preventing marring of the decorated blank from which the can body is formed.

The body blank benders or folders which bend first the double or dovetail hook end of the body blank into final position about the horn, and then the plain hook end thereof about the upper portion of the horn may also be of any suitable kind or construction adapted to perform these functions. The same, however, are preferably horizontally reciprocating ones 11, 12, as indicated in Figs. 41 and 42, and each furnished with a yielding or spring pressed member.

The plunger or bumper 226 which compresses the interlocked hooks of the joint or seam and completes the formation of the seam may also be of any suitable kind or construction adapted to perform this function. It, however, is preferably furnished with a yielding or spring pressed member 230, as will be understood from Fig. 42 of the drawing.

The body blank conveyer by which the can body blanks are conveyed or fed, one by one, first to the hook formers or edge folding devices of the machine, then to the preliminary body blank benders or shapers and then to the body former horn, may be of any suitable kind or construction adapted to perform this function, the same, however, preferably consisting of a reciprocating slide 103 furnished with preferably movable fingers or pawls 110, 111, adapted to engage the rear edge of the can body blanks and to ride under the same at the return movement.

The can body extractor or discharge may also be of any suitable kind or construction adapted to perform the function of delivering or discharging the formed can body from the body former horn. The same preferably consists of a pair of reciprocating hooks or fingers 231, and the same are preferably reciprocated by the same means which reciprocates the body blank conveyer 103.

A general idea of the invention set forth

and claimed in this case can best be gathered from Figs. 24 to 30 and 39 to 44 inclusive.

The blank 1 shown in Fig. 24 passes through the first set of dies designated generically by the reference character 2 and is made into the blank 3 shown in Fig. 26. It is further acted upon by the same dies 2 which change one end to the form at the right of Fig. 28, so that the blank 3 becomes the blank 4 and at the same time the dies at the left of Fig. 29 designated generically by the character 5, fold the left end, as shown. The dies 5 do not act until the dies 2 have acted, as shown in Fig. 27 for reasons that will appear below.

The blank has remained stationary in the machine while being changed from the condition shown in Fig. 24 to that shown in Fig. 28, except that it has been shifted a slight distance transversely of the direction of its feed, and then it is passed to the benders or folders 6, which act on it at each end and simultaneously bend it to the condition shown in Fig. 29 and thereby form the blank 7. The blank is held stationary while the folders 6 act and this is the second pause which the blank makes in its movement through the machine. The third pause is made when it is carried, by means which will be described below, under the horn 8 where it is fixedly held by a clamp 9 and brought up against the horn 8 by means of suitable rollers 10, after which the end of the blank with the double hook is pressed against the horn 8 by means of a jaw 11 and immediately thereafter a second jaw 12 acts to force the other end of the blank into the hook and places the same in the position shown in Fig. 43 when the horn 8 expands, causing the ends to interlock, as shown in Fig. 42, and then the plunger 226 descends and causes the ends to finally interlock and occupy a position which is a little tighter than that shown in Fig. 44.

The mechanism for actuating the various elements above described will now be set forth.

The frame.—The double hook former or edge folder 2 is carried on a suitable bed 13 which is supported by suitable legs 14 or other suitable means. The bed 13 has two rearwardly extending projections 15, which are united near the rear of the machine by an upwardly extending bracket 16 in which some of the mechanism is mounted in a manner which will be described below. Some of the legs 14 are fixed to the bed 13 near the bracket 16, so that the said bed 13 is supported by four legs. The bed 13 carries a number of pedestals in which shafts are journaled and also other supports for other mechanism.

The hook formers or folders.—The folder 2 is mounted near the front of the machine and to the right of the center thereof and is

held in place by bolts or screws 2^a or other suitable means. The mechanism in the folder 2 is driven by means of the main shaft 17, which is journaled in suitable pedestals 18 and 19 as well as in the folders 2 and 5. Near the right hand end of the shaft 17 is mounted a driving pulley 20 by means of which the shaft 17 is rotated. All the movable mechanism of the machine is driven either directly or indirectly by the main shaft 17.

The folder 2 has its mechanism driven by cams 21 22 and 23, the cam 23 being a double cam with two surfaces 24 and 25, both of which are active and each of which is independent of the other, and these cams are separated by a suitable groove so that neither will interfere with the other.

The shaft 17 is provided with the usual key-way and the cams mounted thereon are provided with corresponding keys, which slide in said key-way, but prevent any relative angular movement between the cams and the shaft 17. This construction permits the folder 2 to be moved as a unit so as to be adjusted for various sizes of blanks. The cam 21 is made cylindrical with projecting integral collars 26 and 27, which form a groove between them and these collars 26 and 27 are interrupted by a slot on the periphery of this cam 21, which slot extends parallel to the axis of the cam and contains a slide 28, which is adjustably mounted therein and held in place by suitable cap screws 29. The slide 28 is shown in Fig. 20 and is provided with two cam surfaces 30 and 31, which are slightly curved, as shown so as to break the regularity of the collars 26 and 27 and cause the roller 32 moving therein to move in a direction parallel to the axis of the shaft 17 once in each revolution. The amount of this movement, as will appear below, is very slight and the adjustments to be made for varying thicknesses of metal as well as for wear are still much less in amount. For these reasons the adjustment of the slide 28 in the cam 21, being very small, may easily be provided for. A roller 32 which runs in the groove between the collars 26 and 27 and surfaces 30 and 31, is mounted on a head 33, on the shaft 34 of the bolt 35 and this bolt 35 is held in place by means of a nut 36 and a set screw 37 in a slide 38. The slide 38 is shown in a perspective view in Fig. 18 and is preferably shaped as shown, so as to be free to slide in the frame 39. The frame 39 has a suitable slide-way for the slide 38 and this slide 38 is held in place by suitable strips 40 secured by screws 41. The left end of the slide 38 is grooved on its lower edge to receive a holder 42 which secures a folder 43 and a gage 44, all of which are shaped substantially as shown. The holder 42 is secured in place by means of suitable screws 45 and cap

screws 46, passed through slots in the holder 42 and folder 43 extending into threaded holes in the gage 44 to secure the same in place and at the same time to sandwich in the folder 43 between the gage 44 and holder 42. The dowel pins 47 fix the folder 43 with regard to the holder 42 so as to prevent any sliding of one with regard to the other. The gage 44 is adjusted by means of set screws 48 which extend through lugs 49 on the slide 38 and adjacent to the holder 42. By means of these screws 48 a very delicate adjustment is made possible.

The upper left hand side of the frame 39 carries a cross bar 50, which is held in place by suitable cap screws 51 and the inner and lower edges of this bar 50 are recessed to receive the fixed formers 52 and 53 respectively. Fig. 19 is a perspective view of these formers. The formers 52 and 53 are held in proper relation one with another by means of dowels 54 and screws 55 which extend through the bar 50. The screws 55 extend loosely through the bar 50 and former 53 and are screw-threaded at their inner ends in the former 52 so as to draw the same forcibly into place and hold the former 53 properly. The lower edge of the former 52 is made convex, as shown at 56, for a reason that will appear below: and adjacent to this edge 56 the former 53 is provided with a recess 57, which is substantially of the shape shown. The groove 57 causes a sharp edge 58 to be given to the former 53, as indicated, and this edge 58 is an active element of the former.

The cam 21 is kept in its proper position on the shaft 17 by the frame 39, which it rubs against at one end and a sleeve 59 which it rubs against at the other. The sleeve 59 rubs against a web 60 in the frame 39 and the shaft 17 is journaled in this web 60 and has a bearing therein. The web 60 has the cam 22 rubbing against it and this cam is shown in detail in Figs. 22 and 23 and is nothing more than a plain cylinder with a projection 61 formed substantially, as shown, with substantially tangent walls and a substantially flat top and this cam 22 is engaged by a roller 62, which is mounted on an eccentric sleeve 63 secured on a bolt 64 that is fixed in a vertically movable slide 65. The lower end of the slide 65 is provided with a stud shaft 66, which is made square at one end, that is, the end next the web 60, and at its other end is provided with an eccentric head 67 and a flange 68, which acts as a guide and an annular roller 69. This annular roller 69 is also held in place by means of a bushing 70 between it and the slide 65. The roller 69 turns against the cam 25. This cam is preferably shaped as shown in Figs. 20^a and 21, so that at the right time it always lowers the slide 65 promptly and positively, and this cam 25 is

so arranged and disposed with regard to the cam 22 that it will not interfere with this cam and its roller 62.

From the foregoing it is obvious that by 5 means of the cams 22 and 25 the slide is always properly raised or depressed. The stud shaft 66 is held in place and in proper adjustment by means of a set screw 71.

The upper and left hand corner of the 10 slide 65 is recessed to receive a folder 72 which is secured in place by screws or any other suitable means and is provided with a concave upper surface 73, which is adapted to fit against the lower surface 56 of the former 52. Obviously, this folder 72 always moves with the slide 65 and has no relative movement thereto.

The cam 24 runs against a roller 74 which is mounted on an eccentric pin 75 that is 20 fixed in a small slide 76 held in place by set screw 77. The upper surface of the slide 76 is adapted to press against the lower surface of the former 53 so as to hold a portion of a blank against said former with a gentle 25 pressure, which is not sufficient to prevent it from sliding when necessary because of the action of the dies. The slide 76 slides in slide 65 which is properly recessed to receive the slide 76 and the slide 65 moves in suitable 30 grooves in the frame 39 and is held in place by means of the gibs 78, which are fixed by cap-screws 79.

The folder 5 is at the left of the center of the front of the machine. This folder 5 is 35 composed of a frame 81 and other parts. The frame 81 is secured to the bed 13 of the machine by means of a screw 82 and a clamp 83, in the conventional manner, and the same as the frame 39 of the folder 2. This frame 40 81 is adjusted according to the size of the blank which is folded into the can body. The frame 81 has a suitable bearing 84 for the shaft 17, which shaft carries two cams, one 85 which is within the frame 81 and a 45 second cam 86, which is just outside of the same and adjacent to the bearing 84. The cams 85 and 86 are preferably connected by an integral bushing which revolves in the web 84 and these cams and bushing are 50 keyed to the shaft 17 the same as the cam 21, so that when the frame 81 is shifted on the bed 13, the cams 85 and 86 will be shifted to correspond. The cam 85 is shaped as shown, with a groove that is offset through a portion 55 of its length for a purpose that will appear below. The cam 86 is provided with two steps of increasing diameter and the rest of it is cylindrical, the idea being to have the cam raise the roller 87 twice, which runs thereon, and this roller is depressed once. Fig. 6^a shows the nature of this cam. The roller 87 is mounted the same as the rollers 69 and 62, that is, on an eccentric pin or bushing so as to enable adjustments to be 60 made for varying thicknesses of blanks and

for wear. This roller 87 is mounted on a pin 88 of the kind just described which is held in a rocker arm 89 pivoted at 90 on a suitable pivot which is held in place by the frame 81 and at the top thereof. This rocker arm 89 is shaped substantially, as shown, and is provided with an arm 91 running laterally therefrom and adjacent to the roller 87; and to this arm 91 is secured a coil spring 92, which runs to a pin 93 fixed 75 in the bottom of the frame 81, so that the coil spring keeps the roller 87 on the cam 86 at all times. The end of the rocker 89, which is near the center of the machine, is provided with a former 94 that presses the tin against a clamp plate 95 fixed in the frame 81 and so arranged and disposed that the end of a blank which is to be folded is held between said folder and holder. The tightness of this holding or clamping of the plate depends upon the position of the roller 87 on the cam 86. When the roller 87 is on that part of the cam nearest the center the former 94 and clamp plate 95 are separated sufficiently to enable a blank to be acted upon 80 to slide between them. When the roller 87 rises to the first step on the cam 86 the clamp is firmer, but is not sufficient to prevent the blank from sliding slightly without injuring its ornamental surface. When the roller 87 rises on the part of the cam 86, which is farthest from the center, the blank is clamped between the holder 95 and former 94 so as to prevent all movement. However, 85 this clamping pressure is not sufficient to mar the ornamental surface of the blank. The cam 85 has a roller 96 running therein and this roller 96 is mounted on a pin 97 the same as the roller 87 on the pin 88, that is with an eccentric mounting to permit the adjustment, and this pin is vertically disposed 90 in a slide 98, which runs between suitable guides 99, so as to have neither a horizontal nor a vertical movement, but a compound of the two, that is a diagonal movement of 95 approximately forty-five degrees to either a horizontal or a vertical plane. The lower and inner end of this slide 98 is provided with a former 100 shaped substantially, as shown, and adapted to take under a blank held between the former 94 and clamp 95 and fold the same over the projecting corner of the former 94. A gage 101 rests on the former 100 when the same is in its lowest position and said gage slides freely in its holder 102 so as not to interfere materially with the movement of the former 100 when the former rises. The holder 102 is secured in the frame 81 in a suitable manner.

It is obvious from the above description 125 that the cam 85 gives the roller 96 a longitudinal movement only, which is changed to a diagonal movement by the slide 98 and its mounting so that the former 100 moves in a diagonal path over the projecting corner of 130

the former 94. A fuller illustration of this movement can be gathered from Fig. 29 where the parts are shown detached in order that the operation of the device may be clear.

The body blank conveyer or feed slide.—The slide 103 for carrying the blanks from one part of the machine to another, is mounted on suitable brackets 104 mounted 10 on the bed 13 of the machine and held in place by means of suitable cap screws 105. The brackets 104 are provided with parallel grooves 106, in which the inturned flanges 107 of the slide 103 are adapted to run 15 whereby the slide is held properly on said brackets. The rear ends of the brackets 104 are united by crossings at the front and rear and a plate or band 109 of sheet metal rests on the blocks 108 and is stretched between them. This strip 109 is immediately 20 above the slide 103 which moves under this strip and is exactly the same width as the slide 103. The slide 103 carries a number of 25 pawls some of which are fixed and some of which are spring-pressed. The fixed pawls 110 are nearest the front of the machine and have hook ends adapted to engage the edge of a blank and move the same toward the rear of the machine, a distance of little 30 less than the throw of the slide. The other pawls are identical so that a description of one will answer for all. Each pawl 111 is pivoted on a pivot 112 near the rear edge of the slide 103 and has a lug 113 projecting 35 toward the front of the machine which is connected with a pin 114 near the lower edge of the slide by a coiled spring 115 which normally holds the pawl 111 against a pin 116 in a slot 117 of the pawl 111. The 40 rear end of the pawl 111 is slightly recessed and shaped substantially as shown, so that when sliding under a blank it will be lowered and pressed against the blank with a pressure that is not sufficient to scratch the 45 blank, and on its forward movement will spring up and press against and push the same forward. When the slide 103 moves the pawls 110 take the blank from the place where the operator places it on the band 50 109 and shift it to the folders 2 and 5. From there the blank is carried by the first fingers 111 to the benders 6, and the next set of fingers 111 take the blank from the bender 6 to under the horn 8. The slide 103 55 is provided on its interior with a downwardly extending lug 118 which is pivotally connected to a link 119 that is pivotally connected to an arm 120 fixed on a shaft 121 which is journaled in the bed 13 of the 60 machine. The shaft 121 is provided at the end on the left of the operator with a crank 122 that is pivotally connected with an extensible link 123 that runs to a rocker arm 124 in the machine shown in Fig. 4. This rocker

arm is pivoted at 125 to a lug extending 65 from the bed 13 of the machine and is slot- 70 ted in its upper end to form a guide for a cross-head 126 which is moved by a crank- 75 pin 127 and a crank 128 which is fixed to the main shaft 17 of the machine. A much sim- 75 pler transmitting mechanism is shown in Fig. 31 where the position of the crank 122 is shifted and the link 123 correspondingly shifted and connected directly to the crank 128 which is fixed to the shaft 17. The ro- 80 tary movement of the crank 128 around the axis of the shaft 17 gives an oscillating movement to the crank 122 and a corre- 80 sponding oscillating movement to the shaft 121 which makes the arm 120 have a similar oscillation. This arm moves the slide 103 as above described.

The guides for the body blanks.—On each side of the brackets 104 are suitable guides 129 and 130 respectively. The guide 129 85 runs to the folder 5 and the guide 130 runs to the folder 2. Each guide is provided with a pin 131 which acts as a stop to limit the movement of the blank when the pawls 110 pass thereunder and prevent the blank 90 being carried backward by said pawls. Each guide is shaped substantially as shown, and provided with a suitable oil cup 132 with a wick 133 running up to the guide to which it is attached. These wicks perform 95 the function of lubricating the blanks so that each blank will carry sufficient oil to prevent injury to it and also facilitate the action of the folders, and no more. Without this lubrication the blanks would be 100 scratched and thereby damaged. Another wick 109^a is held by a suitable support 109^b over the strip 109. The support 109^b is 105 preferably carried on the rocker arm 89 of the folder 5. This wick touches the band 109 each time the rocker arm moves down and allows a blank to pass under it while being fed in; this places a very small amount of oil on the band 109 and the blanks carry enough along the band to prevent scratching. 110

The second set of guides 134 and 135 connect the folders 5 and 2 respectively with the benders 6. These guides are very short and are shaped as shown and are simply grooved pieces of metal, so that a further description is unnecessary. 115

The body blank benders or shapers.—The benders 6 are each identical, except that one is adapted to bend the left end of the blank and the other the right, one being the reverse 120 of the other. For this reason a description of one will answer for both. Each bender 6 is secured to a bracket 136 secured either to the folder 2 or to the folder 5. Obviously each bracket is shaped so as to fit the side 125 to which it is attached; that is, one is the right and one is the left. Each bracket 136 has a block 137 fixed thereon by suitable cap

screws 138. The blocks are united by a suitable shaft 139 and on which is mounted a suitable bending tool 140, shaped substantially as shown, and provided with a second and 5 similar shaft 141, which is provided with a block 142 secured to a connecting rod 143 that runs to a second block 144 that is pivoted on a pin 145 on a crank 146. One of the rods 143 is slightly offset so as to clear 10 the other rod 143. The crank 146 is driven by a rod 147 which has a cam roller near its lower end which roller is mounted on a pin 148, and this roller runs in a suitable cam groove 149 in a cam disk 150 which is fixed 15 to a suitable shaft 151 which is carried by suitable bearings 152 secured to the bed of the machine. At its forward end the shaft 151 carries a bevel gear 153 that meshes with a similar bevel gear 154 on the shaft 17 and 20 by which this shaft 151 is rotated. The crank 146 is on a small shaft 155 mounted at the top of the casting 16 and this shaft 155 carries a crank 156 at its rear end, the purpose of which will be described below. 25 *The clamp.*—Before the blanks reach the folders 2 and 5 and while they are sliding on the band 109 they pass between said band and a clamp 157 and this clamp acts on said blank both while it is under the action of 30 the folders and under the action of the benders and is found to be necessary to prevent the blank from buckling while being acted upon by the folders and holds the blank stationary while being acted upon by the benders. 35 The clamp 157 is mounted in the following manner. Its forward end is pivotally connected to a link 158 which runs diagonally upward to a cross-bar 159 the ends of which are fixed in suitable supports 160 40 which extend from the guides 129 and 130 respectively. The cross-bar 159 has two collars 161 one on each side of the link 158, and one of these collars 161 has a downwardly and rearwardly extending arm 162 to which 45 a coiled spring 163 is secured, which spring runs to a screw 164 secured in the clamp 157. A second spring 165 surrounding a pin 166 presses against said clamp and downwardly on the same and against a projection 167 secured to the frame work of the machine. The principal portion of this frame work 50 will be described below.

From the foregoing description of the clamp it is obvious that it is spring-pressed 55 and does not hold the blanks positively except to a slight extent by the spring pressure exerted directly by the spring 165, and indirectly by the spring 163 through the link 158. This spring pressure is sufficient 60 to prevent the blanks from buckling when being bent at their ends and is not sufficient to scratch or cause them to be scratched while passing through the machine.

Body-forming mechanism.—The body-

forming mechanism centers around the horn 65 8 and the parts connected therewith will now be described.

The blank is brought from the benders 6 by the fingers 111 and shoved by them over the clamp 9 under the horn 8 where it is 70 clamped in the following manner: The body 13 of the machine has a shaft 168 journaled therein on which is a small crank 169 which is pivotally connected with the arm 170 which has a projection on which is a roller 75 that runs in a cam groove 171 in the cam 172 which is fixedly mounted on a shaft 173 that is suitably journaled in the machine parallel to the shaft 151, above described. The arm 170 is substantially parallel with 80 the arm 147 and operates the crank 169 exactly the same as the arm 147 oscillates the crank 146, so that no further description of the arm is necessary. It is sufficient to say that the cam groove 171 is shaped substantially as shown, so as to give the crank 169 the proper oscillation. The shaft 173 is driven by a suitable bevel gear 174 on the main shaft 17 which meshes the corresponding gear 175 on the shaft 173. The rear 90 end of the shaft 168 is provided with a crank 176, similar to the crank 156, which is fixed on said shaft and pivotally connected to the extensible link 177 and the upper end of this extensible link 177 is pivotally connected to a cross-head 178 that runs vertically between suitable guides 179 in the conventional manner, and in the upper end of this cross-head 178 are parallel and vertically disposed perforations which receive 100 the vertically disposed rods 179^a of the clamp 9 and these rods 179^a are connected near their lower ends by a crossing 180 which rests on pins 181 so as to hold the lower ends of said rods 179^a in their proper 105 parallel relation, and these pins are contracted at their lower ends and provided with lock nuts. These pins 181 move in suitable sockets 182 in which are suitable coil springs 183. The sockets 182 are fixedly 110 connected to the cross-head guides 179. When the cross-head 178 is in its lowest position, it impinges against the bar 180 and lowers the same against the action of the springs 183, and as soon as this cross-head 115 leaves its lowest position, the coil springs force the rods 179^a upward so that a blank is held by a gentle but firm pressure against the horn 8 by the clamp 9 until the center of the bifurcated arms has reached the limit 120 of their upward movement. Then clamp 9 is supported and itself supports the end of the horn while slide 226 comes down and presses the seam in its final form. After the can body is completed and immediately 125 before it is drawn off the horn, the rod 180 is forced downward by said cross-head and thereby carries the rods of the clamp 9 and

causes the clamp to release the blank. After the blank is clamped under the horn 8 by the spring pressure of the clamp 9, cross-head 178 raises a little farther until its bifurcated arms 185 pass on each side of the horn 8 when its rollers 10 engage the blank and bend the same around the horn. These rollers 10 act simultaneously and co-operate with said horn to form the lower half of the can body about said horn. The next elements to act on the blank are the benders or fingers 11 and 12 preferably slides moving horizontally and near the rear of the machine, as shown, said slides being each provided with a suitable guide 186 secured to the machine by means of bolts 187 and slots 188 and these slides are also provided with a bolt 189 at the lower end of each extending through a lug 190 by which they may be given proper adjustment so that the machine can be adapted for various sizes of cans.

The respective slides 11 and 12 are each provided with two members an upper and 25 a lower. Each lower member has a pin 191 fixed therein which protrudes through a slot 192 in the upper member 193 and the pin 191 is connected by a coil spring 194 to a second pin 195 fixed in the upper member 30 193. The cam actuating mechanism which will be described below is also connected to the upper member 193 so that the lower portion of each slide is free to retreat from the horn and not advance as far as the upper member which is always moved positively. 35 Each slide 193 is provided with ears 196 made substantially as shown and are pivotally connected with an extensible link 197 that runs to a lever 198 which is suitably pivoted at its lower end to a part of the frame work 13 of the machine and at its upper end is pivotally connected with said link 197.

On the rear end of the shaft 151 is a suitable disk 199 in which is a cam groove provided with a suitable roller secured on the lever 198 so that the rotation of the shaft 151 causes an oscillating movement of said lever 198 and produces a corresponding movement of the slide 12. The slide 11 is similarly moved by a similar cam disk 200 on the rear end of the shaft 173 and these cam disks 199 and 200 are each provided with suitable cam grooves so that the slides 50 55 11 and 12 will move properly as above described, and as will be described below.

Immediately in front of the bearing 201 and next to the cam disk 200 and mounted on the shaft 173 is a collar 201 with a cam groove 202 similar to the collar 85 on the shaft 17, and this groove 202 holds the roller on the lower end of a lever 203 which is pivotally mounted on the framework of the machine and vertically disposed, and at its

upper end this lever 203 is pivotally connected with a link 204 which is also pivotally connected to a small crank 205 on the shaft 206 which is journaled in suitable bearings 207 secured to the upright 16 in any suitable manner. These connections, just above described, cause the shaft 206 to oscillate above its axis. The inner end of the shaft 206 is suitably journaled in an elbow 208 secured to the upright 16 in any suitable manner, as by bolts 209 that run 75 into a plate 210 which is fixed by bolts 211 to said upright 16 so that the elbow 208 is held indirectly by said upright 16. The lower end of the plate 210 is provided with a hollow enlargement 212 to which is secured the horn 8. The elbow 208 at its lower end is enlarged to form a guide 213 in which moves a slide 214 with a slight horizontal movement in the direction of the medial line of the machine. This slide 214 receives its movement through a link 215 which is pivotally connected therewith and also with a crank 216 fixed to the shaft 206. The rear and lower end of the slide 214 is provided with a wedge 217 that runs rearwardly through the enlargement 212 and into the horn 8, as shown in Fig. 8, the forward end of this wedge 217 being considerably enlarged and tapering gradually toward the rear and made rectangular in 95 cross-section.

The lower portion 219 of the horn 8 is fixed to the enlargement 212 and on this slides the wedge-portion 217, the upper part 218 of the horn 8 has an inclined lower surface that fits snugly against the wedge 217 so that the same is separated from the lower portion 219 of the horn 8 by a parallel movement. A coiled spring 220 and suitable pins 221 in both the upper and lower parts 218 and 219 and a spring 220^a at the other end act together to draw these parts 218 and 219 together when the wedge 217 permits this action. The collar 201 is so arranged and disposed that the wedge 217 is forced forward when the slides 11 and 12 are closest together. In other words, the wedge 217 expands and contracts the horn 8 at the proper time, which will be described more in detail below.

The horn 8 has a slot 222 on its upper member 218 and a slot 223 on each side of the upper member 218, and near the lower edge thereof, as will appear below.

The rear of the support 16 is provided with suitable guides 224 secured by suitable cap screws 225, and between these guides 224 runs a vertically disposed cross-head or plunger 226 which is connected with the crank 156 by means of an adjustable link 227. The lower end of the plunger 226 is provided with a suitable slot 228 in which are coiled springs 229 between the plunger

226 and a folder 230 which rests in said slot 228 and is movably mounted therein in the customary way. This folder bends the blank in a manner which will be described 5 below.

The oscillation of the shaft 155, above described, causes the crank 156 to have a corresponding oscillation, which oscillation reciprocates the cross-head or plunger 226, 10 said reciprocation taking place so as to complete the seam of the blank in the manner described below.

At this time it is sufficient to say that after the blank has been pressed about the horn, first by the rollers 10, then by the folder 11 and finally by the folder 12, the horn is then expanded by the wedge 217 so that the parts of the seam interlock and then the plunger 226 distends and crushes 20 the seam in the slot 222 so that the joint shown in Fig. 44 is formed when the blank is completed. The wedge 217 is then withdrawn thereby reducing the size of the horn 8 and allowing the can body to be withdrawn 25 therefrom by means of the hooked fingers 231 which are passed forward over the outside of the blank and then have their hooked ends enter the slots 223 on each side of the horn 8, and as these fingers 231 30 treat to the rear of the machine they draw the can body with sufficient momentum to have it fall into the chute 232 from whence it slides to a suitable receptacle.

Can body discharger.—The mechanism 35 for holding or supporting and actuating the can body discharger or fingers 231 is as follows. Each finger is connected to the other finger by means of a suitable coiled spring 233 secured to suitable pins 234 said spring 40 yieldingly connecting the fingers so that they may pass or hook over a can body on their rearward stroke, and these fingers 231 are suitably mounted in a cross-head 235 that runs on parallel guides 236 and is oscillated by means of suitable links 237 which are connected to each arm of a suitable crotch 238 that is pivoted at 239, and at its lower end the crotch has a downwardly projecting arm 240 which is connected by a pivot 45 to the connection and the other end of this link 241 is connected to a lever 242 fixedly mounted on the shaft 221. The lever 242 is practically a continuation of the lever 120 which moves the slide 103 in the manner described above. The link 241 is made adjustable, as shown.

Operation.—In view of the foregoing, the operation of my improved machine will be readily understood. The blank 1 is first placed on the stationary plate or strip 109 and from thence passes under a wick 109^a mounted in a suitable support 109^b which lubricates the upper surface of the band 109 and the blank, and the blank thus car-

ries a small amount of oil along with it and 65 keeps the band 109 oiled so as to prevent injury to the blank. The hooks of the fingers 110 first pass under the blank 1 thereby raising the same a little and when it falls the ends of the hooks are in front of the blank. 70 The blank is then taken toward the rear of the machine for the operation of the dies 2 and 5. The die 2 acts first, as above described, and after clamping the edge of the sheet with a pressure which is not too great 75 between the lower surface of the folder 53 and the slide 76, the plunger 72 is then elevated and forces the edge of the blank into the position shown in Fig. 27 against the edge 43 and the lower surface of the former 80 52. While being so bent the blank slides gently between the clamp 76 and the folder 53. The plunger 72 then retires to its lower position and the edge 43 moves transversely, as shown in Fig. 29, and thereby gives the 85 peculiar shape to the edge of the blank shown in Figs. 28 and 29. Simultaneous with the operation shown in Fig. 29, the other edge of the blank is bent as shown in Fig. 29 by the folder 5 which has a bender 90 100 to bend the edge about the projection of the part 94 while the blank is held near this edge by the part 94 and the clamp 95. When the dies 2 and 5 have completed their operations the blank is released by the respective clamps 76 and 95 and the moving parts of the dies are withdrawn and then one pair of the fingers 111 which have advanced to the front of the blank press against the edge of the same and force it to the benders 100 6 which act on each side to bend it up substantially as shown in Fig. 30. The operation of these benders is so simple that no explanation is necessary other than that given above. From the benders 6 the blank 7 is passed under the horn 8 where it is held by the clamp 9 against the lower surface of said horn and then the rollers 10 are elevated so as to shape said blank about a portion of said horn as shown in Fig. 40. The 105 folder 11 then advances and places the grooved edge of the blank in the groove 222 on top of the horn 8 and immediately thereafter the folder 12 acts to lay the other edge of the blank in the groove. The horn 8 is 110 then expanded and the plunger 226 descends and mashes the joint to the form shown in Fig. 44 and then farther to form a tight joint, when the blank is complete so far as this machine is concerned. The horn is then 115 contracted and the fingers 231 withdraw the blank from the horn 8 in the manner above described and let it fall into the chute 232 from whence it passes to the receptacle provided to receive it. This operation is repeated indefinitely and the blanks are made in rapid succession so that 30,000 can be made in each working day of ten hours.

The joint when made is powder proof, it can not be destroyed by denting the can, and the entire blank is formed without scratching the highly ornamented surface.

- 5 In the modified construction of double or dovetail hook former illustrated in Figs. 45 and 46, the intermediate or connecting wall x^3 between the parallel walls $x^1 x^2$ is originally formed straight instead of curved as 10 is done by the double or dovetail hook formers illustrated in Figs. 25 to 29.

The modified double hook former shown in Figs. 45, 46 and 47 includes an intermediate member 72^3 having a pivot 72^p about 15 which it may swing slightly under action of the member 72^c to cause it to properly coöperate with the former members 2, 43, 53 and 76^4 .

While I have shown and described one 20 embodiment of my invention, it is not restricted thereto, but may be embodied in various forms, all of which come within the scope of the annexed claims.

What I claim is:

- 25 1. In a machine of the class described, means for guiding a blank, a blank conveyor, a die for shaping one edge of a blank into a double reverse fold hook, said die comprising fixed and movable parts, one of 30 said movable parts adapted to form two parallel walls spaced apart and connected by a curved portion bent inwardly between these parallel walls.

2. In a machine of the class described, 35 a double or reverse fold hook former comprising a fixed folder 53, a clamp 76, a fixed folder 52 with a convex lower edge, a folder 72 with a concave upper edge and a slide 43 and means for guiding said slide, means 40 for guiding said folder 72, and means for actuating said clamp 76 and means for conveying a body blank thereto.

3. In a machine of the class described, 45 fixed folders 53 and 52, a movable clamp 76, a movable folder 72 adapted to coact with a curved surface of the fixed folder 52, means for actuating said clamp 76 so that it will clamp a blank loosely while the folder is active, and tight when the said folder 72 is 50 not active, means for advancing and withdrawing said folder 72, a folder 43 and means for causing the same to move transversely of the direction of movement of the folder 72 and after the folder 72 is withdrawn whereby a blank is folded so as to 55 form a dove-tailed groove at one edge.

4. In a machine of the class described, a 60 fixed folder 53, a fixed folder 52 with a convex lower surface a clamp 76 adapted to co-operate with said fixed folder 53 and means for moving said clamp 76 so that it will hold a blank, a folder 72 with a concave surface adapted to coact with the convex

lower surface of the fixed folder 52 and means for moving the folder 72, a folder 43 65 and means for moving the same after the folder 72 has come to rest, a folder 5 and means for actuating the same after the folder 72 has come to rest so as not to interfere with the movement of a blank while 70 being acted upon by said folder 72.

5. In a machine of the class described, means for supporting a blank, means for bending one edge of said blank so that two portions of the same will be parallel to each 75 other and spaced apart and connected by a curved portion and means for straightening said curved portion and folding toward each other said parallel portions to converge and form a dove-tail when taken with the connecting portion.

6. In a machine of the class described, means for forming a blank by bending all bent parts simultaneously with parallel walls at one edge, spaced apart, connected 85 by a curved portion bent inwardly between these parallel walls and means for inclining toward each other said parallel walls to form a double or reverse fold hook.

7. In a machine of the class described, 90 means for clamping a blank, means for forming a groove at one edge of said blank with parallel walls spaced apart and connected by a curved portion, means for changing said curve into a straight portion 95 and converging said parallel walls and means for simultaneously with said last mentioned operation folding the opposite edge of the blank.

8. In a machine of the class described, 100 combination with devices for forming a dovetail hook at one end of a can body blank of a fixed folder and a movable folder 140 and means for actuating said movable folder.

9. In a machine of the class described, 105 combination with devices for forming a dovetail hook at one end of a can body blank of a pair of fixed folders and a pair of movable folders 140 adapted to bend the opposite edges of a blank simultaneously and 110 means for operating said movable folders.

10. In a machine of the class described, the combination with devices for forming a 115 hook at one end of a can body blank, of devices for forming a dovetail hook at the opposite end of said blank, a horn with grooved sides and top, and means for bending a blank about said horn.

11. In a machine of the class described, the combination with devices for forming a 120 hook at one end of a can body blank, of devices for forming a dovetail hook at the opposite end of said blank, a horn with fixed and movable parts, a groove in the top of said horn, means for folding a blank about 125 said horn, means for causing one part of said

- blank to interlock with another and means for mashing said interlocked portions whereby a tight joint is formed in said blank.
12. In a machine of the class described, 5 the combination with a conveyer for can body blanks, of means for forming a dovetailed groove at one edge of a blank and a hook at the other, means for bending each edge of said blank and means for forming 10 said blank into a can body and causing said edges to interlock with abutting bends, so that the same is four-ply thick and no more.
13. In a machine of the class described, 15 the combination with a conveyer for can body blanks, of means for forming a dove tailed groove at one edge of a blank and a hook at the opposite edge, means for bending said blank adjacent to said edges, means for bending said blank so as to form a can 20 body, means for causing the interlocking of said edges, with abutting bends, so that the same is four-ply thick and no more and means for withdrawing the can body from the machine.
- 25 14. In a machine of the class described, means for receiving a blank, means for moving said blank, means for folding said blank at opposite edges so as to form a dove-tailed groove at one edge and a hook at the other, 30 means for bending said blank adjacent to said edges, and means for moving said blank to means for forming said blank into a can body and causing the said edges to interlock and form a tight joint.
- 35 15. In a can body making machine, the combination with devices for forming a hook at one end of a blank, of devices for forming a hook and a reverse fold and consequent dovetail groove at the opposite end 40 of the blank, a can body former horn and a body blank conveyer, substantially as specified.
16. In a can body making machine, the combination with devices for forming a hook at one end of a blank, of devices for 45 forming a hook and consequent dovetail groove at the opposite end of the blank, of benders for shaping the end portions of the blank adjacent to the hooks formed thereon, a body former horn and a body blank conveyer, substantially as specified.
17. In a can body making machine, the combination with devices for forming a hook at one end of a blank, of devices for 50 forming a hook and reverse fold and consequent dovetail groove at the opposite end of the blank, a can body former and a body blank conveyer, means for bending the blank around the horn and interengaging its 55 hooks, substantially as specified.
18. In a can body making machine, the combination with devices for forming a hook at one end of a blank, of devices for 60 forming a hook and a reverse fold and consequent dovetail groove at the opposite end 65 of the blank, a can body former horn and a body blank conveyer, means for bending the blank around the horn and interengaging its hooks, and a bumper for pressing the seam, substantially as specified.
19. In a can body making machine, the combination with devices for forming a hook at one end of a blank, of devices for forming a hook and consequent dovetail groove at the opposite end of the blank, of 70 benders for shaping the end portions of the blank adjacent to the hooks formed thereon, a body former horn and a body blank conveyer, and a bumper for pressing the seam, substantially as specified.
20. In a can body making machine, the combination with devices for forming a hook at one end of the body blank, of devices for forming a dove tail hook at the opposite 75 end of the body blank, a body former horn, devices for bending the middle portion of the blank about the lower portion of the horn and devices for successively bending the free ends of the blank about the upper portion of the horn and causing their hooks 80 to interengage, substantially as specified.
21. In a can body making machine, the combination with devices for forming a hook at one end of a body blank, of devices for forming a dove tail hook at the opposite 85 end of the body blank, a body former horn, devices for bending the middle portion of the blank about the lower portion of the horn and devices for successively bending the free ends of the blank about the upper portion of the horn and causing their hooks 90 to interengage, and a bumper for pressing the seam, substantially as specified.
22. In a can body making machine, the combination with devices for forming a hook at one end of the body blank, of devices for forming a dovetail hook at the opposite end of the body blank, a body former horn, devices for bending the middle portion of the blank about the lower portion of the horn and devices for successively bending the free ends of the blank about the upper portion of the horn and causing their hooks 95 to interengage, a bumper for pressing the seam, substantially as specified.
23. In a can body making machine, the combination with hook forming devices for one end of the blank, of dovetail hook forming devices for the other end of the blank, 100 a body former horn, a body blank conveyer, means for closing the blank about the horn, and means for forming a seam by the engagement of the hooked ends of the blank 105 so that the seam is nowhere more than four-ply in thickness.

24. In a can body making machine, the combination with hook forming devices for one end of the blank, of dovetail fold forming devices for the opposite end of the blank, a body former horn with fixed and movable parts and a body blank conveyer. 5
25. In a can body making machine, the combination with hook forming devices for one end of the blank, of hook and reverse fold forming devices for the opposite end of the blank to produce a dovetail groove therein, a body former horn and body blank conveyer, and movable rollers for bending the middle portion of the blank about the 10 horn, substantially as specified. 15
26. In a can body making machine, the combination of hook forming devices for one end of the blank of hook and reverse fold forming devices for the opposite end 20 of the blank to produce a dovetail groove therein, a body former horn and a body blank conveyer, and movable rollers for bending the middle portion of the blank about the horn, and movable benders for 25 bending the end portions of the blank successively about the horn, substantially as specified. 30
27. In a can body making machine, the combination with hook forming devices for one end of the blank, of hook and reverse fold forming devices for the opposite end of the blank to produce a dovetail groove therein, a body former horn and a body blank conveyer, movable rollers for bending 35 the middle portion of the blank about the horn, and movable benders for bending the end portions of the blank successively about the horn, and a bumper for pressing the seam, substantially as specified. 40
28. In the can body making machine, the combination with hook forming devices for one end of the blank, of dovetail fold forming devices for the opposite end of the blank, benders for shaping the end portions 45 of the blank adjacent to the hooks thereon, and a body former horn with fixed and movable parts substantially as specified. 50
29. In a can body making machine, the combination of hook forming devices for one end of the blank, of hook and reverse fold forming devices for the opposite end of the blank to produce a dovetail groove therein, benders for shaping the end portions 55 of the blank adjacent to the hooks thereon, and a body former horn and a body blank conveyer, substantially as specified. 60
30. In a can body making machine, the combination with hook forming devices for one end of the blank of hook and reverse fold forming devices for the opposite end of the blank to produce a dovetail groove therein, benders for shaping the end portions 65 of the blank adjacent to the hooks thereon, a body former horn, a body blank 70
- conveyer and devices for bending the middle portion of the blank about the horn substantially as specified. 75
31. In a can body making machine, the combination with hook forming devices for one end of the blank, of hook and reverse fold forming devices for the opposite end of the blank to produce a dovetail groove therein, benders for shaping the end portions of the blank adjacent to the hooks thereon, a body former horn, a body blank 80 conveyer, devices for bending the middle portion of the blank about the horn, and devices for successively bending the end portions of the blank about the horn, substantially as specified. 85
32. In a can body making machine, the combination of hook forming devices for one end of the blank, of hook and reverse fold forming devices for the opposite end of the blank to produce a dovetail groove therein, benders for shaping the end portions of the blank adjacent to the hooks thereon, a body former horn, a body blank conveyer, and devices for bending the blank about the horn and devices for successively bending 90 the end portions of the blank about the horn, and a bumper for pressing the seam against the horn, substantially as specified. 95
33. In a can body making machine, the combination of hook forming devices for one end of the blank, of hook and reverse fold forming devices for the opposite end of the blank to produce a dovetail groove therein, benders for shaping the end portions of the blank adjacent to the hooks thereon, a body former horn, a body blank conveyer, devices for bending the middle portion of the blank about the horn, devices for successively bending the end portions of the blank about the horn, a bumper for 100 pressing the seam against the horn, and a device for discharging the can body from the horn, substantially as specified. 105
34. In a can body making machine, the combination with hook forming devices for one end of the blank, of dovetail fold forming devices for the opposite end of the blank to produce a dovetail groove therein, having means for first producing an open groove as a first step and then inclining the walls 110 of the groove at a successive step, means for thereafter causing a positive engagement of opposite ends of the blank, and means for closing the seam so that the curved edges will abut and the same will nowhere be 115 more than four-ply in thickness. 120
35. In a can body making machine, the combination with hook forming devices for one end of the blank, of dovetail fold forming devices for the opposite end of the blank 125 having means for first producing an open groove as a first step and then inclining the walls of the groove at a successive step, a

body former horn with fixed and movable parts, a body blank conveyer, and means for closing the seam so that the curved edges will abut and the same will be nowhere more than four-ply in thickness.

36. In a can body making machine, the combination with a hook former for one end of the blank, of a hook and reverse fold former for the opposite end of the blank to 10 form a dovetail groove therein, a can body former horn, a body blank conveyer, means for bending the blank around the horn, means for interengaging the hooks at the ends of the blank and means for compressing said hooks and folds into a non-collapsible lock seam, substantially as specified.

37. In a can body making machine, the combination with a hook former for one end of the blank, of a dovetail fold former 20 for the opposite end of the blank, said dovetail fold former being adapted to operate to first produce an open groove and then to incline toward each other the walls of said groove, an expansive horn, and means for 25 closing the seam so that the curved edges will abut and the same will be nowhere more than four-ply in thickness.

38. In a can body making machine, the combination with a hook former for one end 30 of the blank, of a dovetail fold former for the opposite end of the blank, said dovetail fold former being adapted to and operating to first produce an open groove and then to incline toward each other the two walls of 35 said groove, a body blank conveyer, an expansive horn, and means for closing the seam about the horn so that the curved edges will abut and the same will be nowhere more than four-ply in thickness.

40. 39. In a can body making machine, the combination with a hook former for one end of the blank, of a dovetail fold former for the opposite end of the blank, said dovetail fold former being adapted to and operating 45 to first produce an open groove and then to incline toward each other the walls of said groove, an expansive body former horn, a body blank conveyer, and means for closing the seam so that the curved edges will abut 50 and the seam will be nowhere more than four-ply in thickness.

40. In a can body making machine, the combination with a hook former for one end of the blank, of a hook and reverse fold 55 former for the opposite end of the blank, said hook and reverse fold former being adapted to first produce an open groove and then to incline toward each other two walls of said groove, benders for shaping the end 60 portions of the blank adjacent to the hooks thereon, a body former horn and a body blank conveyer, substantially as specified.

41. In a can body making machine, the combination with a hook former for one end

of the blank, of a hook and reverse fold 65 former for the opposite end of the blank, said hook and reverse fold former being adapted to first produce an open groove and then to incline toward each other two walls of said groove, benders for shaping the end 70 portions of the blank adjacent to the hooks thereon, a body former horn, a body blank conveyer, devices for bending the middle portion of the blank about the horn, devices for successively bending the end portions of 75 the blank about the horn, substantially as specified.

42. In a can body making machine, the combination with a hook former for one end of the blank, of a hook and reverse fold 80 former for the opposite end of the blank, said hook and reverse fold former being adapted to first produce an open groove and then to incline toward each other two walls of said groove, benders for shaping the end 85 portions of the blank adjacent to the hooks thereon, a body former horn, a body blank conveyer, devices for bending the middle portion of the blank about the horn, devices for successively bending the end portions 90 of the blank about the horn, said horn having an expandible segment, substantially as specified.

43. In a can body making machine, the combination with a hook former, for one 95 end of the blank, of a hook and reverse fold former for the opposite end of the blank, said hook and reverse fold former being adapted to first produce an open groove and then to incline toward each other two walls 100 of said groove, benders for shaping the end portions of the blank adjacent to the hooks thereon, a body former horn, a body blank conveyer, devices for bending the middle portion of the blank about the horn, devices 105 for successively bending the end portions of the blank about the horn, said horn having an expandible segment, and a bumper for pressing the seam, substantially as specified.

44. In a can body making machine, the 110 combination with devices for clamping a blank, of hook forming devices for one end of the blank, of hook and reverse fold forming devices for the opposite end of the blank to produce a dovetail groove therein, substantially as specified.

45. In a can body making machine, the combination with devices for clamping a blank, of hook forming devices for one end of the blank, of hook and reverse fold forming devices for the opposite end of the blank to produce a dovetail groove therein, and means for causing said clamping devices to loosely clamp and to tightly clamp the blank during different parts of the operation of said hook and reverse fold forming devices, substantially as specified.

46. The combination with a body former

- horn, of a reciprocating slide having arms adapted to pass astride the horn, and provided with rollers to engage the blank and bend its middle portion about the horn, devices for forming a plain hook at one end of the blank, devices for forming a dovetail hook at the opposite end of the blank and a body blank conveyer, substantially as specified.
- 10 47. The combination with a body former horn, of a reciprocating slide having arms adapted to pass astride the horn, and provided with rollers to engage the blank and bend its middle portion about the horn, and reciprocating devices for successively bending the end portions of the blank about the horn, devices for forming a plain hook at one end of the blank, devices for forming a dovetail hook at the opposite end of the blank and a body blank conveyer, substantially as specified.
- 15 48. In a can body making machine, the combination with a body former horn, of a clamp for clamping the blank against the horn at its middle, a slide having forks fitting astride the horn and provided with rollers to engage the blank and bend it about the horn, devices for forming a plain hook at one end of the blank, devices for forming a dovetail hook at the opposite end of the blank and a body blank conveyer, substantially as specified.
- 20 49. In a can body making machine, the combination with a body former horn, of a clamp for clamping the blank against the horn at its middle, a slide having forks fitting astride the horn and provided with rollers to engage the blank and bend it about the horn, and reciprocating benders operating to successively bend the end portion of the blank about the horn, devices for forming a plain hook at one end of the blank, devices for forming a dovetail hook at the opposite end of the blank and a body blank conveyer, substantially as specified.
- 25 50. In a can body making machine, the combination with hook formers for forming oppositely turned hooks upon the opposite ends of a body blank, one of said hook formers having means for producing a reverse fold and thereby in connection with the hook, a dovetail groove in one end of the blank, of benders for shaping the end portions of the blank adjacent to the hooks and an expansive body former horn, substantially as specified.
- 30 51. In a can body making machine, the combination with hook formers for forming oppositely turned hooks upon the opposite ends of a body blank, one of said hook formers having means for producing a reverse fold and thereby in connection with the hook, a dovetail groove in one end of the blank, of benders for shaping the end portions of the blank adjacent to the hooks and a body former horn, and a body blank conveyer for advancing the blank first to said hook formers, then to said benders and then to said horn, substantially as specified.
- 35 52. In a can body making machine, the combination with hook formers for forming oppositely turned hooks upon the opposite ends of a body blank, one of said hooks being a double reverse fold hook, of benders for shaping the end portions of the blank adjacent to the hooks, a body former horn, and a body blank conveyer for advancing the blanks first to said hook formers, then to said benders and then to said horn, means for folding the blank around the horn, substantially as specified.
- 40 53. In a can body making machine, the combination with hook formers for forming oppositely turned hooks upon the opposite ends of a body blank, one of said hooks being a double reversefold hook of benders for shaping the end portions of the blank adjacent to the hooks, a body former horn, and a body blank conveyer for advancing the blanks first to said hook formers, then to said benders and then to said horn, means for folding the blank around the horn, and a bumper for compressing the seam against the horn, substantially as specified.
- 45 54. In a can body making machine, the combination with hook formers for forming oppositely turned hooks upon the opposite ends of a body blank, one of said hooks being a double reversefold hook of benders for shaping the end portions of the blank adjacent to the hooks, a body former horn and a body blank conveyer for advancing the blanks first to said hook formers, then to said benders and then to said horn means for folding the blank around the horn, and a bumper for compressing the seam against the horn, and a can body discharging device, substantially as specified.
- 50 55. In a can body forming machine, the combination with hook formers for forming oppositely turned hooks upon the opposite ends of a body blank, one of said hooks being a double reversefold hook of benders for shaping the end portions of the blank adjacent to the hooks and a body former horn, and a body blank conveyer for advancing the blanks first to said hook formers, then to said benders and then to said horn, and guides for guiding the blank from said hook formers to said benders, substantially as specified.
- 55 56. In a can body forming machine, the combination with hook formers for forming oppositely turned hooks upon the opposite ends of a body blank, one of said hooks being a double reversefold hook of benders for shaping the end portions of the blank ad-

5. jacent to the hooks, a body former horn, and a body blank conveyer for advancing the blanks first to said hook formers, then to said benders and then to said horn, guides for guiding the blank from said hook formers to said benders, and guides for guiding the blank from said benders to the horn, substantially as specified.

57. In a can body making machine, the combination with hook formers for forming oppositely turned hooks upon the opposite ends of a body blank, one of said hooks being a double reversefold hook of benders for shaping the end portions of the blank adjacent to the hooks, a body former horn, and a body blank conveyer for advancing the blanks first to said hook formers, then to said benders and then to said horn, guides for guiding the blank from said hook formers to said benders, guides for guiding the blank from said benders to the horn, and a clamp for clamping the blank against the horn, substantially as specified.

58. In a can body making machine, the combination with hook formers for forming oppositely turned hooks upon the opposite ends of a body blank, one of said hooks being a double reversefold hook of benders for shaping the end portions of the blank adjacent to the hooks, a body former horn, and a body blank conveyer for advancing the blanks first to said hook formers, then to said benders and then to said horn, guides for guiding the blank from said hook formers to said benders, guides for guiding the blank from said benders to the horn, a clamp for clamping the blank against the horn, and folders for doubling the blank about the horn, substantially as specified.

59. In a can body making machine, the combination with hook formers for forming oppositely turned hooks upon the opposite ends of a body blank, one of said hooks being a double reversefold hook of benders for shaping the end portions of the blank adjacent to the hooks, a body former horn, and a body blank conveyer for advancing the blanks first to said hook formers, then to said benders and then to said horn, guides for guiding the blank from said hook formers to said benders, guides for guiding the blank from said benders to the horn, a clamp for clamping the blank against the horn, and folders for doubling the blank about the horn, substantially as specified.

60. In a can body making machine, the combination with hook formers for forming oppositely turned hooks upon the opposite ends of a body blank, one of said hooks being a double reversefold hook of benders for shaping the end portions of the blank

adjacent to the hooks, a body former horn, 65 a body blank conveyer for advancing the blanks first to said hook formers, then to said benders and then to said horn, guides for guiding the blank from said hook formers to said benders, guides for guiding 70 the blank from said benders to the horn, a clamp for clamping the blank against the horn, folders for doubling the blank about the horn and further folders for bending the end portions of the blank about the horn, 75 said horn having a collapsing and expanding segment, substantially as specified.

61. In a can body making machine, the combination with hook formers for forming oppositely turned hooks upon the opposite 80 ends of a body blank, one of said hooks being a double reversefold hook of benders for shaping the end portions of the blank adjacent to the hooks, a body former horn, a body blank conveyer for advancing the 85 blanks first to said hook formers, then to said benders and then to said horn, guides for guiding the blank from said hook formers to said benders, guides for guiding the blank from said benders to the horn, a clamp 90 for clamping the blank against the horn, folders for doubling the blank about the horn, and further folders for bending the end portions of the blank about the horn, said horn having a collapsing and expanding 95 segment, and a bumper for compressing the seam against the horn, substantially as specified.

62. In a machine of the class described, means for guiding a blank, a die for shaping one edge of this blank into a dovetail groove, said die comprising fixed and movable parts, one of said movable parts being adapted to coöperate with other parts to form two parallel walls spaced apart and 100 connected by an intermediate part, and mechanism for thereafter causing other parts of the die to make a dovetail groove by converging said parallel walls toward 105 each other.

63. In a machine of the class described, means for forming a dovetail groove in one end of a can body blank comprising a fixed folder 53, a clamp 76, a fixed folder 52, a folder 72, and a slide 43 and means for guiding said slide, means for guiding said folder 72, and means for actuating said clamp 76, substantially as specified.

64. In a machine of the class described, fixed folders 53 and 52, a movable clamp 76, 120 a movable folder 72, means for actuating said clamp 76 so that it will clamp a blank loosely while the folder is active, and tight when said folder is not active, means for advancing and withdrawing said folder 72, 125 a folder 43 and means for causing the same to move transversely of the direction of movement of the folder 72 and after the

folder 72 is withdrawn whereby a blank is folded so as to form a dovetail groove at one edge, substantially as specified.

65. In a machine of the class described, a fixed folder 53, a fixed folder 52, a clamp 76 adapted to coöperate with said fixed folder 53 and means for moving said clamp 76 so that it will hold a blank either firmly or loosely, a folder 72, and means for moving the folder 72, a folder 43 and means for moving the same after the folder 72 has come to rest, a folder 5 and means for actuating the same after the folder 72 has come to rest so as not to interfere with the movement of a blank while being acted upon by said folder 72.

66. In a machine of the class described, means for supporting a blank, means for bending one edge of the said blank so that portions of the same will be parallel and connected with an intermediate portion and means for causing said parallel portions to converge and form a dovetail when taken with the connecting portion, means for forming a plain hook on the opposite end of the blank, means for forming the blank into a can body and interengaging said hook with said dovetail and means for compressing the hook and the walls of the dovetail 30 into a non-collapsible lock seam, substantially as specified.

67. In a machine of the class described, mechanism for forming a blank with parallel walls at one of its edges and then converging said walls toward one another, said walls being connected by an intermediate portion, said mechanism operating to form said walls simultaneously throughout the length of the blank, means for forming a hook on the opposite edge of the blank, means for forming the blank into a can body and interengaging said hook with one of said converging walls and means for compressing the hook and the walls into a non-collapsible lock seam.

68. In a machine of the class described, means for clamping a blank loosely or tightly, means for forming a groove at one edge of said blank with parallel walls connected by an intermediate portion, means for converging said parallel walls, and means for simultaneously with said last mentioned operation, folding the opposite edge of the blank, substantially as specified.

55. 69. In a machine of the class described, means for forming a dovetailed groove at one edge of a blank and a hook at the other edge, an oval horn with grooved sides and top, said oval horn having its longer diameter upright, rollers for bending the middle portion of the blank about said horn, and jaws for bending the end portions of the blank about said horn, substantially as specified.

70. In a machine of the class described, means for forming a dovetailed groove at one edge of a blank and a hook at the other edge an oval horn with fixed and movable parts, said oval horn having its longer diameter upright, a groove in the top of said horn, rollers for folding a blank about said horn, means for causing one part of said blank to interlock with another and means for mashing said interlocked portions into a non-collapsible lock seam whereby a tight joint is formed in said blank, substantially as specified.

71. In a machine of the class described, means for forming a dove-tailed groove at one edge of a blank and a hook at the other, means for bending each edge of said blank and means for forming said blank into a can body and causing said edges to interlock so as to form a seam with bent portions abutting and four-ply thick, and means for conveying the blanks, substantially as specified.

72. In a machine of the class described, means for forming a dove-tailed groove at one edge of a blank and a hook at the opposite edge, means for bending said blank adjacent to said edges, means for bending said blank so as to form a can body, means for causing the interlocking of said edges, means for conveying the blanks, and means for withdrawing the can body from the machine, substantially as specified.

73. In a machine for making can bodies of a single sheet of material having interlocking, non-collapsible, side seams, means for forming a V-shaped hook on one edge of the blank, means for forming a dovetail fold hook on the opposite edge of the blank, and an expansive horn with means for automatically forming said blank into a can body with a non-collapsible side seam.

74. In a machine for making can bodies of a single sheet of material, having interlocking, non-collapsible, side seams, of means for forming a V-shaped hook on one edge of a blank, means for forming a triangular double fold hook on the opposite sides of the blank, a horn and mechanism for folding the blank about the horn, and means for moving said blank to the horn.

75. In a machine for making can bodies from a single piece of body material having an interlocking non-collapsible uniting joint, intermittently operating means for forming a V-shaped hook on one edge of the body material, intermittently operating means for forming a triangular double fold hook on the opposite edge of the body material, means for forming said body material into a can body whereby the hooked ends are interlocked and formed into a non-collapsible uniting joint or seam.

76. In a machine of the class described,

- means for forming interengaging hooks on opposite edges of a body blank, one of said means for forming hooks having mechanism for forming a dovetail fold, an expansive 5 horn, means coöoperating with this horn for forming a blank into a can body and pressing the interengaging seam hooks into a seam, whereby opposite folds in the completed seam abut against and aline with each 10 other to prevent subsequent disengagement.
77. In a can body forming machine, the combination of a horn adapted to sustain a can body blank and a hammer adapted to co-operate therewith, the horn being made of 15 sections adapted to be separated in the plane of movement of the hammer relatively to the horn, and means coöperating with said horn adapted to hold a body blank about the horn during the movement of said hammer and 20 horn sections.
78. In a can body forming machine, the combination of the following instrumentalities: a hammer, a horn, the hammer being adapted to move to and from the horn, the 25 horn being made of separable sections, means for separating the sections in the direction of the plane of movement of the hammer, and folding instrumentalities adapted to engage a body blank about the 30 horn and hold the said blank during the operation of the hammer.
79. In a can body forming machine adapted to form a lock seam on a can body, the combination of a horizontal horn and a hammer 35 movable relatively thereto, the horn being expansible in the direction of the plane of movement of the hammer, means for expanding the same, side folders adapted to wrap around said horn a blank having hook 40 flanges, said expanding means being adapted to interlock said flanges and the hammer being adapted to descend upon the expanded horn and close together said flanges forming the seam.
80. In a can body forming machine, the combination with a horn made of sections, one of the sections having an anvil, a hammer comprising a movable head and a spring 45 within said head for resiliently opposing the contact of the hammer with the anvil, means for separating the horn sections in the direction of the plane of movement of the hammer, and further means for holding a body blank about the horn in coöoperative relationship with the hammer and anvil.
81. In a can body forming machine adapted to form a lock seam on the narrower side of an oblong can body, a grooved horn long 50 in cross-section composed of two parts with an anvil on the upper part, the parts being adapted to be separated in the direction of the anvil by an intermediate part, mechanism coöperating with the anvil to close the seam, mechanism for wrapping a 55 can body on said horn, and mechanism carrying hooks adapted to enter the grooves in the horn and remove said can body from said horn.
82. In a can body forming machine adapted to form a lock seam on the narrower side of an oblong can body, the combination of a horizontal horn having greater height than width, its upper sides being the anvil on which to close the seam, and the horn expansible vertically, side folders adapted to 65 wrap around said horn a blank having hooked flanges, means for thereupon expanding the horn to interlock said flanges, and a seaming hammer above the horn adapted to descend upon the expanded horn 70 and close together said flanges to form the seam.
83. In a can body forming machine adapted to form a lock seam on the narrower side of an oblong can body, the combination of a horizontal horn having greater height than width, comprising a fixed body portion beneath and a vertically movable anvil portion above, with intervening means for raising and lowering such anvil portion, side folders 75 adapted to wrap around said horn a blank having hooked flanges, means for thereupon operating said intervening means to raise such anvil portion and thereby interlock 80 said flanges, and a seaming hammer above the horn adapted to descend upon the expanded horn 85 and close together said flanges to form the seam.
84. In a can body forming machine adapted to form a lock on the narrower side of an oblong can body, the combination of a horizontal horn having greater height than width, comprising a fixed body portion beneath and a vertically movable anvil portion above, with an interposed longitudinally 90 moving slide having inclined working faces adapted when moved to displace said anvil portion to expand or contract the horn, side folders adapted to wrap around said horn a blank having hooked flanges, means for 95 thereupon operating said slide to expand the horn and thereby interlock said flanges, and a seaming hammer above the horn adapted to descend upon the expanded horn 100 and close together said flanges to form the seam.
85. In a can body forming machine adapted to form a lock seam on the narrower side of an oblong can body, the combination of a horizontal horn having greater height than width, comprising a fixed body portion beneath and a vertically movable anvil portion above, with an interposed longitudinally 105 moving slide having inclined working faces adapted when moved to displace said anvil portion to expand or contract the horn, side folders adapted to wrap around said horn a blank having hooked flanges, an ac- 110

tuating slide adapted by its movement to reciprocate said slide and thereby expand the horn, and a seaming hammer above the horn adapted to descend upon the expanded 5 horn and close together said flanges to form the seam.

86. In a machine of the class described, mechanism for forming a hook at one edge of a blank and mechanism for forming a 10 dovetail fold at the other end of the blank, and mechanism for thereafter forming a seam by causing said edges to engage, so

that parts of the hook and folds abut against each other in the middle of the seam, so that a non-collapsible and dust proof seam is 15 formed.

Signed at the city of New York county and State of New York this 20th day of October, 1909.

EUGENE L. PERRY.
